UNITED STATES PATENT OFFICE.

GEORGE J. HEYMOSS, JR., OF DETROIT, MICHIGAN.

HORSESHOE PAD.

Application filed April 7, 1924. Serial No. 704,564.

To all whom it may concern:

Be it known that I, GEORGE J. HEYMOSS, Jr., a citizen of the United States, residing at Detroit, county of Wayne, State of Michigan, have invented a certain new and useful Improvement in Horseshoe Pads, and declare the following to be a full, clear, and exact description of the same, such as will enable others skilled in the art to which it pertains to make and use the same, reference being had to the accompanying drawings, which form a part of this specification.

My invention relates to an improved horseshoe pad.

An important object is to provide a horseshoe pad adapted to serve as a cushion for the horseshoe supported thereon, which pad is provided with a ground-gripping metal member set on edge and extending forwardly from a heel portion of the pad interior the horseshoe carried by the pad, which member is adapted to first engage the ground and is securely fastened to the pad.

An important feature is the provision of a horseshoe pad of cushioning material having a heel portion and a marginal horseshoe supporting portion and being provided with a metal plate set on edge extending forwardly from the heel portion to form a loop within the horseshoe supported by the pad, which loop projects from the pad to a greater height than the horseshoe supported thereby.

Other objects and meritorious advantages of my invention will more fully appear from the following specification descriptive of the embodiment illustrated in the accompanying drawing and defined in the appended claims.

In the drawings,—

Figure 1 is a plan of my improved horseshoe pad and a horseshoe supported thereon,

Fig. 2 is a sectional view taken on line 2—2 of Fig. 1, and

Fig. 3 is a perspective of the horseshoe pad with the metal portion removed.

My improved horseshoe pad is built of suitable cushioning material such as rubber and comprises a substantially flat marginal portion 10 and a heel portion 12. The marginal portion is adapted to support a horseshoe 14 which is shown as having a toe cleft 16. It will be noted that the heel portion of the pad normally projects to a greater height than the body of the horseshoe supported by the pad. The heel por-

tion is shown as having a roughened ground-engaging surface suitable to prevent slipping of the pad on the pavement.

A pad structure of this general character is old. My improved pad, however, is provided with a metal plate 18 which is set on edge and which extends forwardly from the heel portion of the pad to form a loop disposed within the horseshoe carried by the pad. This loop is here shown as being of the same general shape as the horseshoe, and the ends 20 of the plate may be secured to the heel portion of the pad by rivets 22. The plate is shown as provided with a base 70 flange 24 which rests upon a surface of the pad.

The plate is set on edge and projects from the pad to a height greater than the horseshoe carried by the pad so that in use this 75 plate first engages the ground.

There is a ledge 26 of integral structure with the pad which extends forwardly from the heel portion of the pad to snugly embrace the metal plate 18, the plate being 80 set within the recess formed between this ledge and the heel portion of the pad. In use the plate 18 first engages the ground, and the combined shoe structure has superior merit in preventing slipping upon the 85 pavement.

What I claim is:

1. The combination with a horseshoe, of a horseshoe pad of cushioning material having a substantially flat marginal portion 90 adapted to support the horseshoe, an integral heel portion of normally greater height than the horseshoe supported by the pad, a metal plate carried by the pad, said plate being set on edge and extended forwardly 95 from the heel portion of the pad within the horseshoe carried thereby to form a loop of substantially the same shape as the horseshoe but considerably smaller, said plate projecting from the pad to a greater height 100 than the horseshoe carried by the pad.

2. The combination with a horseshoe, of a horseshoe pad of cushioning material having a marginal horseshoe supporting portion, a heel portion, a metal plate set on 105 edge secured to the pad extending forwardly from the heel portion thereof to form a loop interior the horseshoe supported by the pad, said plate projecting from the pad to a greater height than the horseshoe supported by the pad.

3. The combination with a horseshoe, of

a horseshoe pad of cushioning material having a marginal horseshoe supporting portion, a heel portion, a metal plate set on edge secured to the pad extending forwardly from the heel portion thereof to form a loop interior the horseshoe supported by the pad, said plate projecting from the pad to a greater height than the horseshoe supported by the pad, and a ledge of unitary structure with the heel portion extending forwardly therefrom to closely embrace the metal plate.

4. The combination with a horseshoe, of a rubber horseshoe pad having a substantially flat marginal horseshoe supporting portion, a heel portion of normally greater height than the horseshoe supported by the pad, a metal plate secured to the pad having its ends secured to the heel portion of the pad, said plate set on edge and extending forwardly from the heel portion of the

pad to form a relatively small loop within the horseshoe supported by the pad and projecting from the pad to a greater height than said horseshoe, said pad having a ledge 25 integral with the heel portion extending forwardly therefrom and closely surrounding the metal plate.

5. The combination with a horseshoe, of a horseshoe pad of cushioning material having a marginal portion adapted to support the horseshoe, a heel portion, a metal plate set on edge having its ends secured to said heel portion and extending forwardly therefrom to form a loop within the horseshoe 35 supported by the pad, said plate projecting from the pad to a greater height than the horseshoe carried thereby and having a base flange resting on the pad.

In testimony whereof, I sign this specification.

GEORGE J. HEYMOSS, JR.
